UNITED STATES PATENT OFFICE

ERNEST E. MICHAELS, OF BIRMINGHAM, ALABAMA, ASSIGNOR TO CHICAGO BRIDGE & IRON COMPANY, OF CHICAGO, ILLINOIS, A CORPORATION OF ILLINOIS

DESIGN FOR AN ELEVATED TANK

Application filed February 20, 1933. Serial No. 47,264. Term of patent 14 years.

To all whom it may concern:

Be it known that I, ERNEST E. MICHAELS, a citizen of the United States, residing at Birmingham, in the county of Jefferson and State of Alabama, have invented a new, original, and ornamental Design for an Elevated Tank, of which the following is a specification, reference being had to the ac-

companying drawing, forming a part thereof, in which:

The figure is a perspective view of an elevated tank, showing my new design.

I claim:

The ornamental design for an elevated tank, as shown.

ERNEST E. MICHAELS.
